UNITED STATES PATENT OFFICE

156,213

DESIGN FOR A PYROPHORIC LIGHTER

William J. Condon, Chicago, Ill., assignor to Video Lighter Corporation, Chicago, Ill., a corporation of Illinois

Application October 19, 1948, Serial No. 149,181

Term of patent 3½ years

(Cl. D48—27)

To all whom it may concern:

Be it known that I, William J. Condon, a citizen of the United States, residing at Chicago, in the county of Cook and State of Illinois, have invented a new, original, and ornamental Design for a Pyrophoric Lighter, of which the following is a specification, reference being had to the accompanying drawings, forming a part thereof.

In the drawings:

Figure 5 is an elevation of the other side of the lighter;

I claim:

The ornamental design for a pyrophoric lighter, substantially as shown.

WILLIAM J. CONDON.
